SELF-CLEANING FILTER

Noel Obenshain, Piedmont, W. Va., and Milton A. Sively, Luke, Md., assignors to West Virginia Pulp and Paper Company, New York, N. Y., a corporation of Delaware

Application October 16, 1942, Serial No. 462,240

5 Claims. (Cl. 210—152)

Our present invention relates to self-cleaning filters having special application to the filtration of viscous liquids, as for example, those used as coating compositions or "colors" for paper and other webs and which have high viscosity. Such liquids invariably contain a certain amount of grit and fibers of various kinds and origins, which, when present even in small quantities, interfere with the coating operation and cause streaks on the paper or other web. A further type of impurity which must either be removed or prevented from forming is flakes of solid color which are formed by drying of the material and which subsequently do not revert to their original state of suspension but act in the manner of the grit already mentioned. For this reason it is desirable that the filter be compact so that it may be mounted near the coating apparatus and that it be fully enclosed whereby no opportunity is had for the color to cake or dry out. Furthermore, the loss of filtrate must be small.

It is therefore an object to provide a filter answering the above mentioned requirements which will be self-cleaning by providing for continuously backwashing the filtering elements. Further advantages of our improved device will be apparent hereinafter and the features of novelty will be pointed out in the appended claims. For the best understanding of our invention reference may now be had to the following detailed description taken with the annexed drawings, in which

Fig. 1 is a view in elevation showing the front end of an illustrative embodiment;

Fig. 2 is a view in section taken along line 2—2 of Fig. 1;

Fig. 3 is a view in section taken along line 3—3 of Fig. 1.

Fig. 4 is a view of an improved filter element employed;

Fig. 5 is a view along line 5—5 of Fig. 4;

Fig. 6 is a view in perspective, somewhat diagrammatic, of the device showing parts thereof separated.

Referring more particularly to Figs. 1 and 6, it will be noted that our improved device includes an exterior casing comprised of a head element 10 and a tail element 11 which are adapted to be held together by means of a yoke 12 pivoted to element 11 by pivot 13 and carrying a screw bolt 15 and screw handle 16, such bolt terminating in a head 17 which engages within slot 18 of a lug 19 on tail element 10. Casing element 11 has a rib or flange 21 which engages a recess 22 in element 10, the surfaces in contact being machined to provide a tight fitting and leak-proof container.

Each casing element 10 and 11 is provided with registering filter chambers 24, 24a, respectively, chamber 24a communicating with an inlet duct 25, which in turn registers with duct 25a in casing element 11. Similarly, casing section 11 has a passage 26 for a wash water which registers with a corresponding passage 26a in casing section 10, such passage terminating in opening 27 registering with duct 27a in casing section 11. Also, there is provided an exit passage 28 in casing section 11 leading from the filter chamber 24. Labelled pipe connections 28', 25b, 26' and 27b are shown in Fig. 1 for the inlet and outlet of liquid to be filtered and the inlet and outlet for the wash water.

Casing section 11 has journaled therein a shaft 30, such shaft passing through a stuffing box 31 and having at the other end thereof splines 32 to receive a hub 33 of a filter disc 34, the bore of hub 33 being grooved to receive the splines 32. It will be evident that when the casing members 10 and 11 are clamped together, the chambers 24, 24a for the color or other liquid to be filtered and the wash passages 26, 26a are separated by the filter disc 34 whereby the liquor to be filtered and the washing fluid are constrained to pass through respective of the filter elements 35 arranged radially of the hub 33, several of the filter discs being in simultaneous filtering operation. Bushings 36 and 36a serve to keep the shaft 30 from longitudinal movement. The wash passage 26 terminates preferably in a narrow slit-type nozzle 37 in order that a stream of water of high pressure may be directed against the filter elements as they are moved by rotation opposite such jet. It will be further noted that the path of the liquor to be filtered is in the opposite direction to that of the wash water whereby the strained out particles on the filter elements are back washed and removed by the stream of wash water. Also, the inlet and outlet connections for the color or other liquor to be filtered, and the inlet and outlet connections for the wash water, are all attached to the casing element 11, so that our improved filter may be knocked down, as for cleaning or repair, by simply releasing the clamping yoke screw 15, swinging said yoke out of the way and removing head casing portion 10 without having to remove the pipe connections for the color and the wash water.

In Figs. 2 and 3 are shown in detail the construction of the filter elements consisting of slots 29 in the filter disc 34, such slots being covered by a filter screen 40 which is held in place by a reinforced washer ring 41 (reinforcement 41a)

and a snap ring 42 contained in a groove in the disc 34. This type of construction is an important feature permitting easy replacement of screens and keeping thickness of the disc to a minimum. For most cases the disc need not be more than $\frac{1}{8}$ " thick. The small volume contained within the filtering elements result in minimum loss of filtrate in the back wash discharge.

In order to permit the inspection of the filter elements without interrupting the operation of the device, an inspection door is provided, as shown in Fig. 3, such door consisting of a cover 43, a soft rubber disc 44, a clamp 45, a bolt 46 and wing nut 47. Compression of the rubber disc 44 causes it to expand edgewise, thereby holding 10 the door in place. To inspect the filter elements it is only necessary to reduce or shut off the flow of wash liquid, remove the inspection door by loosening the wing nut 47, and allow the filter disc to rotate past the opening, all without having to interfere with the flow of material being filtered. Also, with suitable tools any filter element may be replaced through this inspection door by stopping rotation of the filter disc for not more than a short time. Since this operation can be performed quickly, it usually is not necessary to take the filter out of service.

It will be seen from the foregoing that our improved self-cleaning filter is compact and simple, requiring only two moving parts, the filter disc 34 and the shaft 30; that the head element is removable by loosening the clamp comprised of the handle 18, and that, moreover, the arrangement of these parts is such that should the casing member 16 stick, it will be forcibly withdrawn upon continued screwing out of the bolt 15 due to the head 17 engaging in the slot 18. When the casing head is removed the filter disc 34 may be readily removed from the shaft 30 for servicing or for inspection of the washing jet 31.

It will be evident that various changes may be made in the specific embodiment herein described, without departing from the spirit of our invention or the scope of the appended claims.

We claim:

1. A self-cleaning filter of the type having separate filter and wash passages and in which the

operations of filtering and back washing are simultaneously performed, such filter comprising a comparatively thin rotary filter disc containing a plurality of filter elements which intercept the filter and wash passages, a casing surrounding said filter disc comprising a first portion and a second portion separable on a section parallel to the plane of said disc and affording access to same when said elements are separated, releasable means for holding said portions together, said first casing portion having an inlet and an outlet for fluid to be filtered as well as an inlet and an outlet for washing fluid and passages for said fluids, said first section also containing a drive shaft for mounting and rotating said filter disc, said second casing portion having passages whose ports register with corresponding ports in said first casing section for completing the circuits of the fluid undergoing filtration and said washing fluid.

2. A self-cleaning filter as per claim 1, in which the filter element consists of a perforated back ing support, a screen, a retaining plate, and means for holding the retaining plate in place, said items mentioned being mounted within the thickness of the filter disc.

3. A self-cleaning filter as per claim 1, in which said second casing section has an inspection door disposed so as to afford access to said filter elements and to the washing fluid passage and of a size sufficient to allow passage of said filter elements therethrough.

4. A self-cleaning filter as per claim 1, in which said filter disc is keyed to said drive shaft but 35 is removable therefrom endwise of the shaft.

5. A filter as per claim 1, in which the releasable means for holding the casing sections together comprises a clamping yoke pivoted upon said first casing portion and removably engaging said second portion by means of a threaded bolt in said yoke having a push and pull connection with said second portion whereby said portions may be clamped together or forcibly separated by properly turning said bolt.
